UNITED STATES PATENT OFFICE.

JAMES BERNARD WILLIAMS, OF MINDEN, LOUISIANA.

MACHINE FOR BAGGING AND WEIGHING GRAIN.

SPECIFICATION forming part of Letters Patent No. 786,475, dated April 4, 1905.

Application filed July 25, 1904. Serial No. 218,137.

To all whom it may concern:

Be it known that I, JAMES BERNARD WILLIAMS, a citizen of the United States, residing at Minden, in the parish of Webster and State 5 of Louisiana, have invented a new and useful Machine for Bagging and Weighing Grain, of which the following is a specification.

This invention relates to certain improvements in machines for weighing and bagging grain of that general class shown and described 10 in Letters Patent granted to me on the 18th day of August, 1903, under No. 736,663.

The object of the invention is to improve the construction and operation of the machine 15 by providing an auxiliary valve for directing the flow of grain or other material from the hopper into the discharge-chutes without affecting the main valve.

The invention consists in the construction 20 and novel combination and arrangement of parts hereinafter fully described, illustrated in the accompanying drawings, and pointed out in the claims hereto appended, it being understood that various changes in form, proportion, and minor details of construction may 25 be resorted to without departing from the principle or sacrificing any of the advantages of this invention.

In the accompanying drawings, forming part 30 of this specification, Figure 1 is a side elevation of the machine. Fig. 2 is an end view. Fig. 3 is an enlarged detail view, partly in section, of the main and auxiliary valves.

Similar numerals of reference indicate corresponding parts in all the figures of the drawings.

The frame of the machine, which may be formed of metal or other suitable material, is preferably forged or cast, as shown, and consists of the supporting-legs 5 and longitudinal side bars 6 and 7, the legs 5 being bent laterally to form feet 8, by means of which the machine may be secured to a platform or other suitable support. Arranged on opposite sides of the supporting-frame and secured in any suitable manner to the longitudinal side bars 6 and 7 are uprights 9, provided with terminal flanges 10, between which are sup-

ported the divergent chutes 11 and 12, said chutes leading from a hopper 13, as shown. 50

Disposed within the hopper 13 at the junction of the chutes 11 and 12 is a main valve 14, which regulates the flow of grain and discharges the same alternately through said chutes. The valve 14 is secured in any suitable manner to a rock-shaft 15, journaled in bearings formed in the flanges 10, said rock-shaft being provided with terminal crank-arms 16 and 17, arranged at right angles to each other, as shown, and connected, respectively, by means of pitman-rods 18 and 19 to the inner ends of the scale-beams 20.

The scale-beams 20 extend longitudinally of the frame and are provided with terminal brackets 21, the latter being fulcrumed in the 65 side bars 6 and 7, as indicated at 22. Pivoted on the brackets 21 are substantially rectangular bag-supporting bails or frames 23, and depending from said frames are threaded rods or hangers 24, to the ends of which are secured adjustable platforms 25. The mouth of the bag is supported in distended position on the bail or frame by rods 26, provided with intermediate bag-engaging spurs or teeth 24', said rods being journaled in the bails and provided with terminal cranks 27, by means of which said rods may be rotated so as to cause the spurs to project downwardly and release the bag after the latter has been filled. 70

The relative position of the crank-arms 16 80 and 17 with respect to the pitman-rods is such that when either of the scale-beams is overbalanced the upward movement of the connecting-rod will bring said rod in direct alignment with its respective crank-arm, or, in other words, on dead-center, as clearly shown in dotted lines in Fig. 1 of the drawings, thereby locking said valve and preventing any further movement of the same until the opposite bag or sack has been filled. 85

As a means for preventing the flow of grain or other material from coming in contact with the main valve or falling on the latter when the scale-beams begin to tilt an auxiliary valve 28 is provided, said valve being pivoted 90 within the hopper 13 above the main valve, as

clearly shown in Figs. 1 and 2 of the drawings. The auxiliary valve 28 is provided with crank-arms 29, to which are pivoted depending rods or hangers 30, the hooked ends

5 31 of which extend in the path of movement of the crank-arms 16 and 17, so that when either scale-beam is tilted or overbalanced the crank-arms of the main valve will engage the hooked ends of the depending rods or hangers and automatically shift the auxiliary valve, thereby protecting the main valve and preventing any inaccuracies caused by the weight of the grain which would otherwise fall on said valve.

15 Pivoted within the chutes 11 and 12 are cut-off valves 32 for preventing the column of grain within said chutes from flowing into the sack after the scale-beams are overbalanced, said cut-off valves being movable to open and 20 closed positions through the medium of rods 33, one end of each of which is connected to the scale-beam and the opposite end thereof to the cut-off valve, as shown.

In operation the grain is fed from a thresher 25 or other source of supply into the hopper, and, assuming the main and auxiliary valves to be in the positions shown in Fig. 1 of the drawings, the grain will flow through the chute 12 into the bag or sack until a predetermined quantity has been delivered thereto, 30 when the scale-beam will tilt. As the scale-beam tilts the initial upward movement of the connecting-rod will shift the main valve to the central position, while a further movement of said rod will cause the crank-arm 16 to engage the hooked end of the adjacent hanger and simultaneously move both the main and auxiliary valves to closed positions, thereby cutting off the supply of grain to the 35 chute 12 and directing it through the chute 11 into the opposite bag or sack. The movement of the scale-beam also serves to automatically close the cut-off valve 32, thereby preventing the column of grain within the 40 chute 11 from flowing into the sack after the main valve is closed.

Having thus described the invention, what is claimed is—

1. In an automatic weighing and bagging 50 machine, a hopper, discharge-chutes leading therefrom, a main valve, scale-beams connected to said valve, and an auxiliary valve arranged in advance of the main valve and operable thereby.

55 2. In an automatic weighing and bagging machine, a hopper, discharge-chutes leading therefrom, a main valve provided with terminal crank-arms, scale-beams connected to said arms, and an auxiliary valve disposed 60 above the main valve and operable thereby.

3. In an automatic weighing and bagging machine a hopper, discharge-chutes leading therefrom, a main valve provided with terminal crank-arms, scale-beams connected to said

arms, an auxiliary valve disposed above the 65 main valve, and depending rods pivoted to the auxiliary valve and extending in the path of said crank-arms.

4. In an automatic weighing and bagging machine, a hopper, discharge-chutes leading 70 therefrom, a main valve controlling the passage of material into said chutes, scale-beams connected to said valve, cut-off valves for regulating the discharge from the chutes and operable by the scale-beams, and an auxiliary 75 valve arranged in advance of the main valve and operable thereby.

5. In an automatic weighing and bagging machine, a hopper, discharge-chutes leading 80 therefrom, a main valve provided with terminal crank-arms, scale-beams connected to said crank-arms, an auxiliary valve pivoted within the hopper, and depending rods pivoted to the auxiliary valve and having their free ends provided with terminal hooks arranged in the 85 path of movement of said crank-arms.

6. In an automatic weighing and bagging machine, a hopper, discharge-chutes leading therefrom, a main valve controlling the passage of material into said chutes, scale-beams 90 actuated alternately by the weight of the material, an auxiliary valve disposed above the main valve and operable thereby, and means connecting the scale-beams to the main valve for changing the position of said valve and 95 positively locking the same with respect to the scale-beam affecting such change of position.

7. In an automatic weighing and bagging machine, a hopper, discharge-chutes leading 100 therefrom, a main valve, scale-beams connected to said valve, an auxiliary valve pivoted within the hopper and provided with angularly-disposed crank-arms, and depending rods pivoted to said arms and having their 105 free ends arranged in the path of movement of the crank-arms of the main valve.

8. In an automatic weighing and bagging machine, the combination with a frame, of chutes, a main valve, a pair of scale-beams 110 fulcrumed on the frame, a cut-off valve controlling the discharge of material from each chute and operable by the movement of the scale-beams, a pivotal connection between the scale-beams and the main valve, and an auxiliary 115 valve disposed above the main valve and operable thereby.

9. In an automatic weighing and bagging machine, the combination with a frame, of a hopper, discharge-chutes leading therefrom, scale-beams fulcrumed on the frame, a main valve connected to the scale-beams, and an auxiliary valve pivoted within the hopper, 120 said valves being simultaneously actuated by the movement of the scale-beams.

10. In an automatic weighing and bagging machine, a hopper, discharge-chutes leading 125 therefrom, a main valve disposed at the junc-

ture of said chutes, scale-beams connected to the main valve and provided with terminal bails or frames, hangers depending from said bails or frames, adjustable bag-supporting platforms carried by the hangers, and an auxiliary valve arranged in advance of the main valve and operable thereby.

In testimony that I claim the foregoing as my own I have hereto affixed my signature in the presence of two witnesses.

JAMES BERNARD WILLIAMS.
